UNITED STATES PATENT OFFICE.

CHARLES E. REDDIG, OF RICHMOND HILL, NEW YORK, ASSIGNOR TO WESTERN ELECTRIC COMPANY, INCORPORATED, OF NEW YORK, N. Y., A CORPORATION OF NEW YORK.

PRIMER AND CHOKE.

Application filed October 19, 1921. Serial No. 508,771.

To all whom it may concern:

Be it known that I, CHARLES E. REDDIG, a citizen of the United States, residing at Richmond Hill, in the county of Queens, 5 State of New York, have invented certain new and useful Improvements in Primers and Chokes, of which the following is a full, clear, concise, and exact description.

This invention relates to improvement in 10 devices for priming and choking internal combustion engines and relates particularly to a single unit which serves both as a primer and choke.

The object of the invention is, in general, 15 to provide means for accurately regulating the amount of air delivered to the manifold of an internal combustion engine, and to provide a simple rugged means, whereby raw fuel may be injected in the manifold 20 for priming the engine.

In accordance with the general features 25 of this invention, the air intake pipe of an internal combustion engine is arranged to deliver air through an orifice in a flat surface and the manifold is arranged to receive air from another orifice in the same flat surface. In sliding engagement with the flat surface is a hollow cup-like member having 2 orifices, and arranged so that it can 30 be rotated to effect any degree of registration between its two orifices and the orifices leading from the air intake and to the engine manifold. In this way the volume of air delivered to the manifold can be regulated.

In order to provide for priming the engine, the rotatable member is provided with a separate compartment having an aperture which can be brought into registration 40 with the orifice leading to the manifold.

An opening allows raw fuel to be poured into this separate compartment from which it runs through the aperture into the manifold.

45 Referring to the drawings:

Figure 1 is a fragmentary vertical section showing the invention in connection with an engine cylinder and a special type of electrically regulated carburetor.

50 Figure 2 is a top plan view, partially in section, showing the carburetor regulator with the cover removed.

Figure 3 is a side elevation of a prime mover dynamo plant in which the prime

mover is an internal combustion engine 55 equipped with the present invention, and showing the relative position of the carburetor regulator, the intake manifold and the combined primer and choke.

Fig. 4 is a fragmentary elevation showing the combined primer and choke device.

Fig. 5 is a vertical sectional view of the primer and choke device in position for air regulation.

Fig. 6 is a vertical sectional view of the 65 combined primer and choke mechanism in position for priming purposes.

Referring now to the drawings in detail, 70 an internal combustion engine cylinder 1, having heat radiating flanges 2 (Fig. 1) is provided with an overhead valve 3 through which an explosive charge is admitted. An intake manifold 4, having communication with the valve chamber, has a constricted neck portion 5. Integral with said manifold and located above said constricted neck portion is a valve housing 6 containing a needle valve 7 the stem 8 of which is threaded so that it may be adjusted by rotation within said housing. A helical spring 75 80 rests upon said housing, serving as a frictional resistance to hold the valve in place.

Beyond the opening of the needle valve and located in a wider portion of the manifold 4, is a butterfly valve 10, rotatably mounted upon a ball-bearing pivot 11, so that it may be easily rotated to any angle desired. The butterfly valve is secured to a stem 12, which is an extension of the axis 85 of an electromagnetic regulator 13.

Accurate adjustment of the amount of air 90 passing through an air passage 14 leading from the crank case 15 (Fig. 3) into the intake manifold 4 is obtained by means of a choking device 17. The choke comprises a cup-shaped receptacle 17 serrated on its circumference (Fig. 4) in order that it may be manually adjusted, and rotatably mounted on a pin 18 which is threaded into the intake manifold 4. A helical spring 19 compressed by a washer 20, which is held in place by a cotter pin 21, serves to keep the cup 17 flush against the walls of the intake manifold 4.

The end 22 of the intake manifold 4 beyond the butterfly valve 10 is open, as is the adjacent side 23 of an air chamber 16 which is in communication with the upper end of

the air passage 14 (Figs. 5 and 6). The combined priming and choke cup 17, comprising an annular rounded chamber 63 and a base portion 64, is pressed against the end 5 of the manifold 4 and the side of the chamber 16 by the spring 19 so as to cover both of the openings 22 and 23. The base 64 of the cup 17 is provided with two diametrically opposite openings 24 and 25, which are 10 equal in diameter to the openings 22 and 23. By rotating the cup 17, the openings 24 and 25 may be brought into partial or total registration with the end 22 of the manifold 4, and the side 23 of the chamber 16, thus permitting 15 air to pass from the chamber 16, through the annular chamber 63 of the priming cup 17, and into the manifold 4. The outer surface of the cup 17 has integral therewith two lugs 26 and 27 located at an 20 angle of approximately 90° from each other which engage a flange 28 of the electromagnetic regulator casing 13, which lugs serve to limit the rotation of the cup 17 to a one-quarter turn in each direction. The face of 25 the cup between the lugs 26 and 27 is graduated for accurately regulating the amounts of air passing therethrough.

The interior of the cup 17 is provided with a partition 31, which forms a separate 30 chamber 66 within the cup for priming purposes. The priming charge is introduced through a hole 30 (Fig. 4) located between the lugs 26 and 27, and is permitted to pass into the intake manifold through a small 35 orifice 32 in the base 64 of the cup 17.

Electromagnetic control of the needle valve 7 and the butterfly valve 10 is obtained by the action of regulator 13. The regulator 13 is contained within a housing, the 40 base 67 of which is made integral with the intake manifold 4. Circular field laminations 37' riveted together at 68 and having pole pieces 36 and 37 integral therewith fit into an annular recess 69 in the base 67. 45 Surrounding the laminations 37' is a split cylindrical shell 70 which is clamped to the field laminations 37' by means of a bolt 71 which passes through ears 72 formed integral with the regulator casing. A cap portion 73 fits securely upon the shell 70.

Regulator field coils 34 and 35 are wound upon the field poles 36 and 37 respectively. A rotatable armature 38 is mounted on the shaft 12 and is supported by a washer 74 55 held in place by a cotter pin 75. A nut 40 fitted over the threaded end of the axis 12 locks armature 38 against washer 74, causing armature 38 and shaft 12 to rotate together. An arm 39, integral with the armature 38 60, is provided with hooks 41 and 42, which serve to hold two helical springs 43 and 44, respectively. The springs 43 and 44, which serve to retard the motion of the armature 38 are rigidly held at their opposite ends by 65 ears 45 and 46 integral with the regulator

casing 13. Adjustable threaded lugs 46 and 47 are fitted into the regulator casing 13 and engage lugs 147 and 48 respectively, which are integral with the armature 38, limiting the motion of the armature to about 30°. 70 A second arm 49 mounted on a pivot 50 is connected with the bifurcated end 33 of the arm 39 through a pin 67 and is rotated thereby through an angle equal to that through which arm 39 is free to move. The needle valve stem 8 is attached to the arm 49 and is rotated in response to movements of the regulator. The needle valve 7 is made adjustable relative to the arm 49 by means of a serrated knob 58 which is attached to the upper portion of the stem 8 and is kept from rotation by means of a lug 51, which is fitted into a recess 52 in the arm 49, and kept in engagement with arm 50 by means of a compression spring 53. 80 The axis, or stem, 12 of the regulator 13 extends through intake manifold 4 where the butterfly valve 10 is attached for rotation therewith.

The coils 34 and 35 are energized through 90 a cable 55 leading from an electric dynamo 68 (Fig. 3), which is driven by the prime mover, and are responsive to the voltage of the dynamo circuit. An increase in voltage in the dynamo circuit causes the armature 95 38 to turn against the action of the springs 43 and 44, closing the butterfly valve 10 and limiting the amount of fuel which is permitted to pass through the needle valve 7; whereas a decrease in voltage, such as occurs 100 when a number of translating devices are added to the dynamo circuit, permits the springs 43 and 44 to contract, turning the armature 38 in a clockwise direction and opening the butterfly valve and simultaneously permitting more fuel to pass from a low level tank 56 through a feed pipe 57 and through the needle valve 7. If the prime mover dynamo system be employed to charge 110 a battery, then the electromagnetic regulator will serve to give the battery a tapering charge as the back C. M. F. from the battery increases and the engine gradually slows down. This method of charging prolongs 115 the useful life of the battery.

The improved construction enables the engine cylinder to draw its entire air supply from the engine crank case 15 and to control the amount of air taken up in this manner by 120 means of the manually adjustable choke 17 and the automatic air valve 10. The air drawn from the crank case is warm and more readily forms a combustible mixture with the fuel. This air also contains unexploded 125 vapors which have leaked by the piston and these vapors are utilized in forming a new explosive mixture. In priming, choke 17 permits a small amount of air to pass from the atmosphere into the intake manifold through orifice 32 together with the priming 130

charge. During normal operation, however, orifice 32 is blocked by the turning of choke 17 and the entire air supply must be drawn from the crank case through intake 14, 5 thence through cup 17 into the intake manifold, where it is subject to the automatic adjustment of load responsive regulator 13 after which it is passed at an increased velocity through the constriction 5, where 10 the decrease in pressure resulting from the rapid passage of the air causes fuel to be drawn directly from low level fuel tank 56 to needle valve 7. At no point in the fuel feeding system is a gravity reservoir or a 15 float controlled chamber employed, but the fuel, on the other hand, is fed directly from the low level tank to the mixing chamber.

The fuel rising in supply pipe 57 enters 20 the needle valve casing 6 at a point 58 and passes through screen 59 before entering the needle valve proper. The screen 59 is placed within a short tube 60 having orifices 61, through which the fuel is fed. A threaded 25 plug 62 permits the tube 60 to be removed, together with the screen 59 so that the screen may be cleaned.

Although the invention is disclosed and described in connection with an internal combustion engine which is employed to drive a 30 dynamo electric machine, it is to be understood that the invention is not limited in this respect, but is to be defined solely by the scope of the appended claims.

What is claimed is:

35 1. In combination with an internal combustion engine, a combined priming cup and choke comprising a hollow receptacle divided into two chambers, a base plate having diametrically opposite orifices therein communicating with one chamber, an intake manifold having an opening in its end adjacent said cup, a crank case, an air passage from said crank case to said priming cup having an opening in its end adjacent said cup, said cup being rotatable so that the openings therein may be placed in registration with the openings in said air passage and said manifold.

40 2. In an internal combustion engine a hollow member provided with an orificed surface which is in sliding engagement with sec-

ond surface having two orifices leading from an air intake pipe, and to the engine manifold respectively, said member being rotatable to regulate the amount of air delivered 55 to the engine manifold.

3. In an internal combustion engine, a hollow member provided with a surface in sliding engagement with a second surface having an orifice leading to the engine cylinder, and a partition dividing said member into an apertured compartment and an orificed compartment, said member being rotatable so as to place either of said compartments in communication with the engine 60 cylinder.

4. In an internal combustion engine having a manifold, a plane surface having a pair of orifices, the first leading to the engine manifold; an air intake pipe having connection in the crank case of said engine and arranged to deliver air through said second orifice; a shutter having perforations disposed to register with said orifices and movable for regulating the amount of air delivered through said orifices to said engine manifold and means for indicating the position of said shutter with respect to said orifices. 70

5. In a primer for an internal combustion 80 engine having an explosive chamber; a surface having an orifice in communication with said explosive chamber; another orifice in said surface connected to an air intake pipe; an apertured hollow member for receiving 85 liquid fuel and for establishing communication with said orifices; said member being movable to cause registration between an aperture in said hollow member and the first mentioned orifice; whereby the engine 90 may be primed with liquid fuel, means to prevent the movement of said member in one direction when the hollow member is in registry with one of said orifices for priming said engine, and means to prevent the movement of said member in another direction when the path through the hollow member 95 and the orifices is established.

In witness whereof, I hereunto subscribe my name this 13th day of October A. D., 1921.

CHARLES E. REDDIG.
